UNITED STATES PATENT OFFICE.

GEORGE HASTINGS HACKETT, OF NORTH SYDNEY, CANADA, ASSIGNOR TO JOHN DAVID COPELAND, OF ANTIGONISH, NOVA SCOTIA, CANADA, DANIEL MCLEAN, WILLIAM JOHN CHRISTIE, SIDNEY SALTER, AND FRANCIS THOMAS LEMOINE, OF NORTH SYDNEY, NOVA SCOTIA, CANADA.

MACHINE FOR PRODUCING PERFORATED TELEGRAPH-PAPER.

SPECIFICATION forming part of Letters Patent No. 711,660, dated October 21, 1902.

Application filed June 12, 1901. Serial No. 64,249. (No model.)

To all whom it may concern:

Be it known that I, GEORGE HASTINGS HACKETT, a subject of His Majesty the King of Great Britain, residing at North Sydney, county of 5 Cape Breton, Province of Nova Scotia, Canada, have invented certain new and useful Improvements in Machines for Producing Perforated Telegraphic Paper; and I do hereby declare that the following is a full, clear, and 10 exact description of the invention, such as will enable others skilled in the art to which it app pertains to make and use the same.

My invention is a machine for perforating or punching paper for the automatic transmission 15 of telegraphic messages by the Wheatstone recorder or other systems of telegraphy on cable or aerial lines.

It is well known that telegraphers stationed in certain offices are required to punch or perforate messages upon strips or ribbons of paper in accordance with the well-known electric 20 telegraphic characters, with this important distinction—*i. e.*, the “dots” of the telegraphic alphabet are distinguished from the “dashes” by arranging the former above a 25 real or imaginary line of demarcation, while the latter appear below such line.

The chief and important purpose of the present invention is to provide a machine in 30 which all the perforations representative of the dots, dashes, or both, required to form a complete letter, figure, or other character may be produced with a space between it and the following letter, character, figure, &c., of 35 the telegraphic code may be produced by the depression of a single key or element in much the same way as the operation of type-writing machines.

A further object of the invention is to provide 40 automatic means for producing a central line of holes or perforations in the paper simultaneously with the formation of the character-indicating perforations, such central line of perforations serving as the line of demarcation for the dot and dash representations 45 of the character and as a means for the engagement of the feeding element of the automatic transmitter and also of a like element of my improved perforating-machine.

A further object of the invention is to improve the perforating-machine in minor details of its several working parts with a view to securing ease in operation, efficiency and accuracy in the work, and to minimize and simplify the elements. 50

With these ends in view the first part of my invention contemplates the employment of two groups of character-punches, each operable individually or in combination with one or more of the same group or one or more 55 of the other group, means for feeding a ribbon or strip in the path of the character-punches, and a series of individually-operable keys or elements, each arranged to have operative connection with one or more punches 60 of either group, according to the number of dots and dashes which is required to be produced in the ribbon or strip to form the letter, ordinal, or character of the usual telegraphic code. 65

The invention further consists in a group of feed-hole punches mounted on a common carrier for simultaneous movement and disposed in co-operative relation to the character-punches of the two groups and adapted to be 70 positively actuated by one or more of such character-punches of either group. 75

The invention further consists of a ribbon or strip-feed mechanism operable automatically by the character-punches or the feed-hole 80 punches and capable of imparting a variable feed to the ribbon or strip according to the number of dot and dash perforations in the letter or character of the code.

My invention further consists in the novel 85 combination of mechanisms and in the construction and arrangement of parts, which will be hereinafter fully described and claimed.

In the drawings hereto annexed, forming a part of this specification, Figure 1 is a plan view 90 of my perforating-machine with a portion of the housing or casing omitted in order to show some of the operating parts. Fig. 2 is a front elevation with a part of the key-guide plate broken away. Fig. 3 is an inverted or bottom 95 plan view of the machine. Fig. 4 is a longitudinal sectional elevation through the machine in the plane of the dotted line 4 4 on

Fig. 1. Fig. 5 is an enlarged sectional plan view through the punch mechanisms and the feed mechanism in the plane of the dotted line 5 5 on Fig. 4. Fig. 6 is an enlarged sectional elevation in the plane of the dotted line 6 6 on Fig. 5 looking in the direction of the arrow. Fig. 7 is a vertical cross-section on the line 7 7 of Fig. 6 looking in the direction of the arrow. Fig. 8 is a detail cross-section on the line 8 8 of Fig. 6. Fig. 9 is another detail cross-section on the line 9 9 of Fig. 6. Fig. 10 is a sectional plan view of the feed mechanism in the plane of the dotted line 10 10 on Fig. 11. Fig. 11 is a vertical transverse section through the feed mechanism in the plane of the dotted line 11 11 on Fig. 10. Fig. 12 is a sectional plan view in the plane of the dotted line 12 12 on Fig. 6, taken through the row of die-openings for the feed-hole punches. Fig. 13 is an enlarged sectional plan view in the plane of the dotted line 13 13 on Fig. 11, showing one group of the character-punches advanced to its operative position. Fig. 14 is a fragmentary view of a strip or ribbon of paper perforated by a machine in accordance with my invention and illustrating the dot and dash perforations and the central row of feed-holes to indicate the letters "a," "b," "c," and "d" of the Morse code. Fig. 15 is a front view illustrating the group of central feed-hole punches and the two groups of upper and lower character-punches in order to more clearly illustrate the relation or arrangement thereof.

35 The same numerals and letters of reference denote corresponding parts in each of the several figures of the drawings.

5 designates the frame, casing, or housing, which may be of any desired or approved construction, although in the embodiment of the invention represented by the drawings it is shown of elongated rectangular shape. Within this housing are supported the transverse bridge-bars 6 6^a, the same arranged in horizontal positions near opposite ends of the casing and secured firmly to the sides thereof by approved means. These bridge-bars are preferably arranged in rear of the bank of keys. They are spaced apart a sufficient distance to 45 accommodate between themselves a number of key-actuated rock-shafts 91 59. They are arranged in the same horizontal plane, and they are provided with a series of vertical slots 7. These slots are arranged in the same 50 horizontal and vertical planes in the two bars 6 6^a, and each slot is deep enough to accommodate two of the character-punch slides. (See Fig. 7.) A confining-plate 7^a is secured to the top edge of each bridge-bar, so as to 55 extend across the open upper ends of the slots 7 therein, and this plate extends across the upper group of slides a b c d e, as will hereinafter more fully appear. The framework of the apparatus or machine is completed by 60 the provision of key-guide plates 8 8^a, which project horizontally from the front side of the housing, and by the employment of a boxing 65

9, which is disposed at one end of the housing 5, said boxing serving to inclose the operating parts forming the feed mechanism for 70 the ribbon or strip which is to be perforated by the groups of punches in accordance with the characters of the telegraphic code. The key-guide plates 8 8^a are disposed in horizontal positions one above the other and in parallel relation, and these plates are firmly secured to the housing, whereby the plates are adapted to serve as the supports for the slideable keys. These keys are indicated by the numerals 53, 54, 55, and 56, and they are arranged in two series, the keys of each series extending longitudinally along the front of the machine, while the keys of one series are disposed in a horizontal plane below the keys of the other series, thus arranging the keys 75 in a bank at the front of the machine. I will have it understood, however, that the framework of the machine may be arranged to include the boxing 9 as an integral part thereof and within the limits of said framework and 80 that the means for supporting the keys may be varied in any manner suggested or approved by the skilled constructor, so as to promote the convenience of the operator in the manipulation of the machine or for any 85 other cause whatsoever. It is evident that the keys may be disposed in a manner similar to the keyboard of a type-writing machine; but this is optional. A practical working machine which I have constructed and operated 90 includes a total of thirty-eight keys, each having a rock-shaft 91 or 59 combined operatively therewith; but I have reduced the machine to a simple condition by the provision of means 95 which enables me to employ a series of ten character-punches, the same adapted to be operated according to certain permutations or combinations with said key-actuated rock-shafts. The character-punches are divided into two groups, arranged to represent, respectively, 100 the dots and dashes of the code, and, as hereinbefore explained, I have found it convenient to follow the established plan of punching the dot-perforations in the ribbon above the line of demarcation therein, while the 105 punches which represent the dash-perforations operate on the ribbon or strip to make said dash-perforations below the line of demarcation. The punches of the two groups are mounted individually on slides, and the 110 slides for the upper series of punches 81 82 83 84 85 (see Fig. 5) are indicated by the reference-letters a b c d e. (See Figs. 7 and 9.) The lower group of character-punches is indicated by the numerals 86 87 88 89 90, (see 115 Figs. 12 and 15,) and said punches of the lower group are carried by the slides f, g, h, i, and j. The slides constituting each group are disposed in the same horizontal plane. The slides forming the lower group f to j, inclusive, are arranged in the slots 7 of the bridge-bars 6 6^a, so as to rest upon the lower ends of the slots and be thereby supported in said 120 bridge-bars, and the slides of the upper group 125

*a to e, inclusive, occupy the upper portions of the slots 7 in the bridge-bars, whereby the slides of the upper series are disposed to rest upon the slides of the lower series. (See Fig. 5. 7.) Each slide is movable longitudinally in the bridge-bars without affecting either of the other slides, and it will thus be seen that each slide is capable of a longitudinal reciprocatory play individually or independently of either of the other slides. The slides extend practically the full length of the frame or housing, so as to lie over the entire series of thirty-eight rock-shafts, and these slides are thus disposed to have slidable relation to each and all of the rock-shafts, which makes it possible for intermediate devices to actuate either of the rock-shafts with any one or more of the upper and lower groups of slides. The slides are adapted to be individually or collectively impelled in a forward direction by the operative connections from said slides to the rock-shafts but the slides are returned back to their normal positions by the action of a suitable impelling-spring, connected operatively with the cross-head 65, (see Figs. 1, 4, and 13,) said slides being individually provided with stop pins or lugs 10, which are arranged to impinge against the bridge-bar 6, and thereby limit the rearward movement of the slides under the action of the retracting-springs 65^a. These character-punch slides are disposed in peculiar relation one to the other, as represented by Figs. 1, 3, 4, 5, 7, and 13, for the purpose of accommodating the means that operatively connect the rock-shafts with the slides. The middle slides *c h* of the upper and lower groups are straight throughout their length. The slides *b d* of the upper group and *g i* of the lower group are bent at points just in advance of the bridge-bar 6, as indicated at 11, in order to make the front portions of the slides lie very close together, while those portions of the slides which lie over the rock-shafts 91 59 are spaced apart and in parallel relation, so as to accommodate the studs on the slides and the fingers on the rock-shafts, and, furthermore, the outermost slides *a e* of the top group and *f j* of the bottom group are also bent inwardly, as at 11^a, in order to bring their front ends in close parallel relation to the corresponding ends of the other slides and enable the portions that extend over the rock-shafts to be spaced laterally and parallel to the other slides of the groups, whereby said slides *a e f j* are also arranged over the rock-shafts for the fingers on certain of the shafts to have operative relation to studs on said designated slides. This construction and arrangement of the slides permits the large number of fingers required for the entire series of rock-shafts to be disposed in working relation to a small number of slides, and, furthermore, the closely-arranged bent front portions of said slides enable the character-punches of the two groups to be compactly disposed with relation one to the other for operation on a*

narrow strip or ribbon of paper and also bring the punches of the two groups in different horizontal planes for operation on the ribbon above and below the line of demarcation therein. The slides constituting each group are nearly of uniform length; but they are slightly foreshortened at their front ends in order to make the slides vary in length just a little, as represented by Fig. 5, whereby the front ends of the slide of each group are slightly staggered, and the punches of each group have their front ends arranged in like staggered order. The two groups of character-punches and a third group of punches adapted to form the feed-holes or the line of demarcation in the paper or ribbon are operatively fitted in a common die-block 12, the latter being arranged in a horizontal position within the compartment of the boxing 9, and preferably secured to the front end wall of the framework 5. This die-block is provided with a central row of six die-openings 13, adapted to receive the group of feed-hole punches 75 76 77 78 79 80. (See Fig. 12.) It is furthermore provided with an upper row of die-openings 14, adapted to receive the five dot-forming character-punches 81 to 85, inclusive, and finally the die-block is formed with a lower row of die-openings 15, five in number, and disposed for the reception of the dash-forming character-punches 86 to 90, inclusive.

16 designates a die-plate which corresponds in form and size to the die-block 12 and is secured to the inner side thereof in the position shown by Figs. 5, 6, 11, 12, and 13, said die-plate being provided with rows of holes 13^a, 14^a, and 15^a, which are arranged in positions corresponding to the rows of holes 13, 14, and 15, respectively, in the die-block, whereby the punches are adapted to pass when advanced from the holes of the die-block into the holes of the die-plate. (See Figs. 12 and 13.) In the face of the die-block, to which the die-plate 16 is secured, is provided a space, channel, or groove 17, through which the ribbon or strip of paper is adapted to be fed in the manner represented also by Figs. 12 and 13, and across this space or channel are adapted to play the character and feed-hole punches, whereby the paper fragments removed from the ribbon or strip by the operation of the punches, due to the process of perforating the paper, are carried through the holes in the die-plate and discharged into the compartment of the boxing 9. The die-plate 16 is provided with a recess or slot 18, which extends through the die-plate from the series of holes 14^a to one edge of the plate, as indicated in Fig. 12, and a recess 18^a is also formed in a part of the die-block in a position coincident with the slot 18 of the die-plate, thus making provision for the accommodation of the pins on the feed-wheel 24, to be presently described.

To allow ready access to the feed mechanism, I have preferably provided the boxing 9 with a removable front slide 19 and with a

similar back slide 20, and in these slides are formed the slots 21 21^a, respectively, which slots lie in the transverse plane of the ribbon-channel 17 in the die-block, whereby the strip 5 or ribbon of paper may be drawn from a spool or reel or other source of supply may pass through the boxing 9 and the ribbon-channel 17 of the die-block, and it may be engaged by the feed-wheel, thus presenting 10 the ribbon in position for the operation of the punches thereon, and allowing the ribbon to continuously pass through the machine.

I will now proceed to describe the preferred embodiment of the feed mechanism, which is 15 arranged to advance the ribbon or strip as rapidly as it is perforated and is operable automatically with either group of punches or with the individual punches of the character-forming elements of the machine.

20 A vertical feed-shaft 22 is journaled in suitable bearings 23 at its upper and lower ends, (see Figs. 6 and 11,) one of the bearings being secured to the bottom of the boxing 9 and the other to the top thereof. The feed-wheel 24 is made fast with this shaft, and it is provided with a multiplicity of pins or studs 25, said feed-wheel and the shaft being arranged in position relative to the die-block for the pins 25 to sweep through the slot 18 and the 25 recess 18^a and to engage with the feed holes or perforations which are formed at the middle of the ribbon by the operation of the feed-hole punches 75 to 80, inclusive. A ratchet-wheel 26 is also made fast with the 30 feed-shaft 22, being arranged, preferably, below the feed-wheel 24, and this ratchet-wheel is rotated intermittently by the action of a pawl 46, which is mounted on a reciprocating feed-rod 27. (See Figs. 5, 6, 10, 11, and 13.) 35 40 This feed-rod 27 is disposed in a horizontal position, so as to pass through a guide-block 28, which is secured to the front end wall of the casing 5, whereby one end portion of the feed-rod is disposed in a compartment of the 45 boxing 9, while the other portion of said feed-rod lies in the casing 5, preferably below the group of character-punch slides. This feed-rod is supported partly in the casing 5 by means of a bracket 29, which is fastened to 50 the front end wall of said casing and has a sleeve 29^a, in which the feed-rod is loosely fitted, and said feed-rod is provided with the stop-collars 30 30^a, (see Fig. 9,) which are disposed on opposite sides of the sleeve 29^a 55 of the bracket, said collars serving to permit the feed-rod to have a reciprocating movement within the required limits. The feed-rod is provided with a threaded rear extremity 31 for the attachment of the cross-head 60 70, which is adapted to be operated by a stop-collar 73 on a reciprocating rod 61, that is actuated by the spacing-key, as will hereinafter more fully appear, (see Fig. 6,) and to the rear threaded extremity of this feed-rod is 65 connected a link 32, which extends over the series of key-actuated rock-shafts and to the other end of the framework through an open-

ing in which said link is arranged to pass in order that it may be connected to the upper extremity of a bell-crank lever 33. (See Fig. 70 4.) Said lever is fulcrumed at its angle, as at 34, to the outside of the casing 5, and to the long arm of this bell-crank lever is connected a powerful spring 35, the same having its other end attached to the framework, as 75 at 37. The energy of the spring 35 normally pulls the feed-rod to the right, so as to maintain the elements of the ribbon-feed mechanism in the normal position, (shown by all the figures of the drawings except Fig. 13,) although the feed-rod 27 occupies an operative relation at certain times to the cross-head 65. Said feed-rod within the compartment of the boxing 9 is formed with a lateral offset 38, (see Fig. 10,) and said feed-rod has an extension 85 39, which is disposed alongside of the ratchet-wheel 26. Said feed-rod extension is provided at a point near the crook or bend with a collar 40, and it carries a bent check-finger 41, the latter being formed at its heel with a 90 socketed enlargement 42, that is fitted on the extremity of the feed-rod extension 39, said enlargement supporting a binding-screw 43, that is adapted to impinge the feed-rod, and thereby clamp the check-finger rigidly to the 95 feed-rod extension. Between the collar 40 and the socketed enlargement 42 on the feed-rod extension is loosely arranged a pawl-carrying sleeve 44, (see Figs. 10 and 11,) said sleeve being capable of a limited movement 100 or play on the feed-rod extension between the collar 40 and the enlargement 42. The pawl-sleeve is provided on one side with a slot 45, in which is arranged the feed-pawl 46, the same being pivoted to the slotted portion of the sleeve, as at 47, and pressed, by means of a spring 48, normally into engagement with one tooth on the ratchet-wheel 26. The feed-rod extension and the pawl-sleeve are supported and guided by a post 49, which 105 is provided with a divided bearing 49^a, that loosely embraces the pawl-sleeve, as shown more clearly by Fig. 11, whereby the feed-rod extension and the pawl-sleeve are upheld by the post, so as to keep the feed-pawl 46 at 110 all times in operative relation to the ratchet 26. When the feed-rod 27 is impelled in a forward direction, either by the action of the spacing-key or by the movement of one or 115 more of the groups of character-punch slides, the feed-pawl 46 slips idly over the teeth of the ratchet and the check-finger 41 is carried away from the ratchet; but when the feed-rod is pulled in a backward direction by the 120 energy of the spring 35 the feed-pawl 46 moves the ratchet 26 an angular distance equivalent to the number of teeth over which the feed-pawl is slipped during its forward movement, the check-finger 41 preventing any idle play of the ratchet owing to the jar 125 which may be given to the machine by the spring 35 or other working elements of the apparatus. On the opposite side of the ratchet 26 from the feed-rod extension is a 130

fixed arm 50, which is secured to the front end wall of the frame 5, and to this arm is pivoted a check-pawl 51, the same being held in engagement with the ratchet by a spring 52, said check-pawl preventing rotation of the ratchet by the frictional engagement of the feed-pawl 46 therewith during the forward movement of said feed-pawl with the feed-rod.

10 The key 53 is the spacing-key, by which and its associated parts the group of feed-hole punches 75 to 80, inclusive, are actuated independently of the character-punch slides for the purpose of making the feed mechanism advance the ribbon or strip independently of the operation of either of the character-keys when it is desired to separate letters or words of the telegraphic code produced by the perforation of the ribbon. The group of 15 twenty-six alphabetical keys (indicated by the numeral 54) are operatively related to the character-punch slides, so as to actuate the same individually, with a view to making the character-punches produce the alphabetical telegraphic code. The key 55 is the character-key which is frequently employed in telegraphy, especially at the beginning and end of a message. The group of ten keys comprised in the reference-numeral 56 are operatively connected through intermediate devices with the group of character-punch slides in a manner to make the latter actuate the character-punches so as to produce in the ribbon the telegraphic-code signs representative of the ordinals from naught to nine, inclusive. The alphabetical and numerical keys 54 56 constitute the two series which are designated, generically, by the term "characters," whereas the keys 53 55 are adapted to 20 make the punches work so as to space the words of the code and to make the inquiry-sign call for an operator at a distant station, respectively. Each key is provided with a stem that is slidably fitted in the plates 8 8^a of the framework, and around the stem of the keys 54 55 56 are coiled the lifting-springs 57, one of which is provided on each key-stem and is seated on the plate 8^a and presses against a pin 57^a, attached to the stem. (See Fig. 7.)

25 50 The spacing-key 53 is arranged to bear at its lower end against an arm 58, which is secured to the first rock-shaft 59 of the series of rock-shafts, and this rock-shaft is provided at a point between the slides *c* and *d* with an upstanding curved arm 60, the latter arranged to ride against a pin or stud 62, which is made fast with a spacing-rod 61. (See Fig. 6.) This spacing-rod is arranged in a horizontal position below the lower group of character-30 punch slides *f* to *j*, inclusive, and its rear portion is slidably fitted in an opening or slot 63, which is provided in the bridge-bar 6. (See Fig. 7.) This spacing-rod 61 has its front end reduced and threaded at 61^a, and it passes 35 through an opening which is provided in a depending lug 68 on the cross-head 65. (See Figs. 6 and 9.) The nuts 69 69^a are screwed

on the threaded extremity 61^a of the spacing-slide and arranged to bear against the opposite sides of the lug 68 of the cross-head 65, 70 whereby the front end portion of the spacing-slide is supported by the cross-head 65 and the spacing-slide and the cross-head are fixedly but adjustably united together. This cross-head 65 is slidably fitted in recesses 66 75 67, which are formed in the opposing edges of the closely-arranged front portions of the upper and lower group of character-punch slides, and said cross-head is normally arranged at the rear portions of said recesses, 80 so that it may be engaged by the shoulders 66^a 67^a of the slides forming the two groups, whereby on the advancement of one or more slides of one or both groups the shoulder or shoulders will press against the cross-head, 85 so as to advance the latter the required distance. This cross-head 65 is drawn normally in a backward direction by the energy of springs 65^a, which are attached to opposite end portions of the cross-head and to the 90 bridge-bar 6, as clearly shown by the drawings, whereby the cross-head and the shoudered portions of the slides are kept normally in their proper operative positions.

The secondary cross-head 70 is fitted slidably in the recesses 71 72, formed in the opposing edges of the upper and lower groups of character-punch slides, and this cross-head is adapted to be engaged by a collar 73, which is fitted on the spacing-key slide 61 at a point 95 in rear of the cross-head, said collar 73 having a binding-screw 74, which makes the collar fast with the spacing-rod 61. (See Fig. 6.) Furthermore, the cross-head 70 is provided with a depending shank 70^a, which is loosely 100 fitted on the threaded rear extremity 31 of the reciprocating feed-rod 27, and this cross-head and the feed-rod are made fast together by the check-nuts 70^b, which are screwed on the extremity 31 of the feed-rod and are disposed to bear against opposite sides of the shank 70^a of said cross-head 70.

The feed-punches 75 to 80, inclusive, are all attached to the cross-head 65 so as to lie in the same horizontal plane and to properly 115 enter the series of holes 13 in the die-block, and all these punches are of uniform length, as clearly shown by Fig. 12. The upper group of character-punches 81 to 85, inclusive, are disposed in the same horizontal plane and 120 are fastened individually to the slides of the upper group *a* to *e*, inclusive, said upper group of character-punches arranged to play in the upper series of holes 14 of the die-block and having their front ends disposed in staggered 125 order, as shown by Fig. 5. The lower group of character-punches 86 to 90, inclusive, are made fast with the slides of the lower group *f* to *j*, inclusive, and they are disposed to work in the lower series of holes 15 in the die-block, and they have their front ends disposed in staggered order similar to the upper group of punches. The punches 75 to 80, inclusive, are six in number, whereas each group 130

of character-punches consists of five parts only, and, furthermore, the feed-hole punches are of smaller diameter than the character-punches. The rock-shafts 91 are associated with the alphabetical and inquiry keys 54, 56, and 55, respectively, and each rock-shaft is provided at one end with an arm 92, the same being disposed in operative relation to the lower extremity of one key-stem and said series of arms being compactly arranged, as shown by Fig. 3, in order to minimize the space. Each rock-shaft furthermore carries one or more fingers 93, and each finger is arranged to impinge or ride against a stud or pin on one of the character-punch slides. The studs on the slides of the upper group are indicated by the numerals 94, and the studs on the slides of the lower group are indicated at 95. It will be understood that the spacing-key does not actuate a character-punch slide, nor is it operatively disposed to a stud on either of the slides of the two groups. Each rock-shaft which is operated by a character-key has a group of fingers corresponding in number to the dot-and-dash punches required to represent the letter in the telegraphic code, and said fingers ride against pins or studs which are placed on slides of the upper and lower groups, so as to individually actuate the slides in the proper order with a view to making the dot-punches above the line and the dash-punches below the line, although all of the punches are operated simultaneously.

By reference to Fig. 14 it will be seen that the ribbon 100 has a central row of feed-holes 101, and said figure shows the telegraphic-code letters "a," "b," "c," "d," the first of which, "a," is made by one dot-perforation above the line and one dash-hole below the line; the second letter, "b," by three dot-holes above and one dash-hole below the line; the third letter, "c," by two dot-holes above the line and two dash-holes below the line, &c. It is evident, therefore, that the rock-shaft 91, which is actuated by the letter-key *a*, must have two fingers 93 arranged to press against a stud 94 on one of the upper group of slides and one stud 95 on one of the lower group of slides, so as to make the punches operate in the sequence of one dot and a dash, as in the telegraphic code. The rock-shaft for the letter-key *b* must be equipped with a series of four fingers 93 arranged to press forward against the studs 94 on three of the upper group of slides and one stud 95 on one of the lower group of slides in the order of making a dash and three dots. The rock-shaft for the letter-key *c* must also be equipped with four fingers 93 so arranged that they will actuate studs 94 on two of the upper group of slides and two studs 95 on two of the lower group of slides, so as to make one dash-perforation, one dot-perforation, another dash-perforation, and another dot-perforation in proper sequence or order. The rock-shaft for the letter-key *d* must have

three fingers 93 arranged to actuate two upper slides and one lower slide to make a dash perforation and two dot-perforations in the necessary sequence, and so on throughout the entire range or series of letters or ordinals.

In operation the space-key 53 may be depressed so as to slide the rod 61 forward and move the cross-head 65 against the tension of the springs 65^a, thus moving the group of punches 75 to 80, inclusive, through the die-block and the die-plate to produce the feed-holes 101 102 in the ribbon, the parts being returned by the springs 65^a to normal position on releasing the finger-pressure. At the same time the collar 73 on the rod 61 is carried forward against the shank 70^a of the cross-head 70, which is loosely fitted on the said spacing-rod 61 and is fast with the feed-rod 27, and this described movement of said feed-rod carries the pawls 46 41 forwardly without advancing the ratchet, the latter being held against idle play by the check-pawl 51. After the spacing-key has been released and the group of punches 75 to 80, inclusive, and the cross-head 65 shall have been returned to normal position, so that the punches are clear from engagement with the paper ribbon, the feed-rod 27 is forcibly returned to its normal position by the energy of the spring 35, and during such return movement the feed-pawl 46 is active to turn the ratchet 26 a proper distance, thereby rotating the shaft 22 and the feed-wheel 24, the pins 25 of which feed-wheel engage the perforations 101 of the paper ribbon, so as to advance the latter a proper distance through the die-block, all the parts returning to the position shown by Figs. 6, 10, 11, and 12. When any one of the character-keys throughout the series is depressed, the proper rock-shaft is actuated and its fingers 93 press against the studs of the upper and lower group of slides, (one or more of each group,) and the slides thus brought into service are pressed forward simultaneously, so as to advance their character-punches for making the dot-and-dash perforations in the paper ribbon in proper order or sequence, as in the telegraphic code, for which sequential order the staggered arrangement of the punches is an important feature in securing the desired operation. As is evident, the forward thrusting of the punch-slides makes them push through the holes in the die-block and the plate, so as to perforate the ribbon, as described, and although the slide 61 is not actuated by the space-key it is moved by another train of connections, because the cross-head 65 is pressed forward by the shoulder or shoulders 66^a or 67^a on the character-punch slides now in service at this particular period, whereby the group of feed-punches 75 to 80 are advanced simultaneously with one or more of the character-punch slides and at the same time the collar 73 is made to press against the cross-head 70, which correspondingly advances the feed-rod 27 and moves the pawls 41 46 to the positions shown by Fig. 13.

On releasing the character-key the springs 65^a pull the cross-head 65 and the advanced character-punches and their slides back to the normal positions, thus moving the spacing-rod 61 and the collar 73 thereon back and from engagement with the cross-head 70, it being evident that the character and feed punches are withdrawn from the paper ribbon before the spring 35 becomes active to 5 return the feed-rod 27 to normal position for the purpose of making the feed-pawl 46 turn the ratchet 26, the shaft 22, and the feed-wheel 24, so as to feed the paper ribbon through the die-block, and thereby present a 10 fresh surface to the action of the punches on the depression of the next key.

In Fig. 13 of the drawings I have represented in full lines the action of the letter-key *b*, by depression of which the rock-shaft 20 59 makes four of the fingers 93 act against the studs on the slides *f b c d* of the two groups of slides for the purpose of advancing the punches 86, 82, 83, and 84 in the sequence described, so as to make one dash-perforation 25 below the line and three dot-perforations above the line, and at the same time the entire group of feed-punches 75 to 80 is advanced for the purpose of punching the series of feed-holes in the paper ribbon.

30 Of course the spacing-key may be actuated to separate words or sentences, and it actuates the feed-hole punches independently of the character-punches and also actuates the feed mechanism to advance the paper ribbon.

35 Changes within the scope of the appended claims may be made in the form and proportion of some of the parts, while their essential features are retained and the spirit of the invention is embodied. Hence I do not 40 desire to be limited to the precise form of all the parts as shown, reserving the right to vary therefrom.

Although I have shown and described the machine as having a particular number of 45 keys and feed-punches, I reserve the right to increase the number of characters and feed-punches whenever it is necessary to punch other characters. I also reserve the right to provide means whereby the speed of the feed 50 mechanism may be increased while the stroke of the punch devices may be one-third or even less and still operate to turn the feed-wheel the proper distance. It is evident that the spring 35 may be placed at the opposite 55 end of the machine or in front of the machine and along the other springs or that any equivalent arrangement may be adopted.

Having thus described my invention, what I claim as new is—

60 1. In a perforating-machine of the class described, the combination of two groups of shouldered slides each carrying a character-punch, a cross-head equipped with a series of feed-hole punches fixed thereto and disposed in the path of the shoulders of said character-punch slides to be actuated by any

one or a group of said slides, means for operating said cross-head and the feed-hole punches independently of said slides, keys having operative connections with the slides 70 for actuating the latter and the character-punches in the order or sequence required to produce the characters in accordance with a code, a feed mechanism operable to move a ribbon in the path of all the punches, and 75 means between said ribbon-feed mechanism and said cross-head for positively actuating said feed mechanism each time the cross-head is advanced, substantially as described.

2. In a perforating-machine of the class described, the combination of a plurality of slides each equipped with a character-punch, a cross-head equipped with a series of feed-hole punches fixed thereto and disposed in operative relation to the slides to be actuated 80 by a single slide or a group of slides, means for advancing the slides and their character-punches to punch holes in a telegraphic tape, a ribbon-feed mechanism comprising a reciprocating rod, a ratchet-wheel adapted to revolve adjacent to said rod but not engaged directly thereby, and a pawl pivotally mounted on said rod adapted to engage the teeth of said ratchet-wheel to advance them during the motion of the rod in one direction and to 90 slide loosely over them during the motion of the rod in the opposite direction, and means between the cross-head-actuating mechanism and said rod to advance the latter subsequent to the advance movement of the feed- 95 holes punches.

3. In a perforating-machine of the class described, the combination of a plurality of character-punches, a cross-head having a series of feed-hole punches fixed thereto, means 100 for holding the cross-head in retracted position, a spacing-bar connected to the cross-head and having operative connection with a spacing-key, a feed mechanism including a reciprocating rod carrying a pawl and a revoluble ratchet-wheel engaged thereby, a stop movable with the spacing-rod and arranged at one point of its movement to have engagement with said reciprocating rod, and a plurality of keys operatively connected with said 105 slides to actuate the character-punches individually or in groups, substantially as described.

4. In a perforating-machine of the class described, the combination of a perforated die-block having a transverse ribbon-feed passage, a revoluble feed-wheel, a reciprocating feed-rod having a check-finger normally engaged with the feed-wheel, a collar loosely mounted on the said rod and having a check-pawl adapted to engage normally with the feed-wheel, a plurality of character-punches arranged to traverse the die-block, a series of feed-hole punches fitted to the die-block, a spacing-key for the feed-hole punches only, 120 a series of keys having operative connection with the character-punches, and intermediate 125

connections between the feed-rod and the actuating devices for the character and feed-hole punches, substantially as described.

5. In a perforating-machine of the class described, the combination of a perforated die-block having a ribbon-feed passage, a feed-shaft having a ratchet-wheel and a feed-wheel, a reciprocatory feed-rod, a check-finger carried by the rod and normally engaged 10 with the feed-ratchet, a sleeve loosely mounted on the rod and having a feed-pawl normally in engagement with the feed-ratchet, a plurality of character-punches, a series of feed-hole punches, means for actuating said 15 feed-hole punches independently of the character punches, and means for actuating the feed-rod each time either of said punches is moved to active position, substantially as described.
- 20 6. In a perforating-machine of the class described, the combination of a perforated die-block having a ribbon-feed passage, a die-plate having perforations in registration with the perforations of the die-block and also provided with a longitudinal recess, a feed-shaft having a ratchet-wheel and a feed-wheel provided with pins and arranged to traverse the recess of the die-plate and to have its pins extend across the feed-passage, a reciprocating 25 feed-rod carrying an idly-mounted feed-pawl and a check-finger arranged to engage the ratchet-wheel, a plurality of character-punches having means for operating the same, a group of feed-hole punches having means 30 for operating the same, and means for actuating the feed-rod each time either or a group of said punches is moved to active position, substantially as described.

7. In a perforating-machine of the class described, the combination of a die-block provided with a ribbon-feed passage, a feed-shaft having a ratchet-wheel and a revoluble feed-wheel, a reciprocatory feed-rod provided with a collar, a sleeve loosely mounted on the rod 45 and carrying a pawl which engages normally with the ratchet-wheel, a check-finger clamped to the rod and arranged to coöperate with the collar in limiting the movement of the pawl-carrying sleeve on said feed-rod, an independently-mounted check-pawl engaging with 50 the ratchet-wheel, a plurality of character-punches having means for operating the same singly or in groups, the feed-hole punches independently operable from a single spacing-key, and means for actuating the feed-rod on the advancement of either or a group of the punches to active position, substantially as described.

8. In a perforating machine of the class described, the combination of a die-block, two groups of character-punches arranged for the punches of each series to occupy staggered relation, means for holding the character-punches in retracted positions, a group of 65 feed-hole punches uniform in length and operable to simultaneously perforate a ribbon, a feed mechanism for advancing a ribbon in

the path of all the punches, means for actuating the character-punches singly or in groups and in the order or sequence required to produce characters in accordance with a code, means for actuating the feed-hole punches separately or in conjunction with the character-punches, and means whereby the feed mechanism is positively actuated on the withdrawal of all the punches to retracted positions, substantially as described.

9. In a perforating-machine of the class described, the combination of a perforated die-block, two groups of shouldered slides each having a character-punch, a cross-head disposed in the path of the shouldered slides and provided with a series of feed-hole punches fixed thereto, a series of keys having operative connections with the slides, a spacing-key having operative connection with the cross-head, and a feed mechanism operated by a train of connections with an element of the spacing-key mechanism, substantially as described.

10. In a perforating-machine of the class described, the combination of a perforated die-block, a series of slides each equipped with a character-punch, a cross-head equipped with feed-hole punches and having operative relation to the slides, a spacing-rod attached to the cross-head and provided with a collar, a spacing-key for actuating the rod, a feed mechanism including a feed-rod as one element thereof and provided with a stop in the path of the collar on the spacing-rod, and a plurality of keys each having operative connection with one or more of the slides, substantially as described.

11. In a perforating-machine of the class described, the combination of two groups of slides, disposed one above the other and movable independently in suitable guides, a character-punch fast with each of the slides, a series of studs on each of the slides, a series of keys, a series of rock-shafts each in active relation to one of the keys and provided with one or more fingers arranged to ride against said studs on the slides, and a feed mechanism having operative connection with the punch-actuating means, substantially as described.

12. In a perforating-machine of the class described, the combination of a perforated die-block, two groups of notched slides each equipped with a character-punch, a spring-retracted cross-head operatively fitted to the notched slides and carrying a series of feed-hole punches, a spacing-bar attached to the cross-head and provided with a collar, a spacing-key connected with said spacing-bar, a feed mechanism having a spring-retracted feed-bar, a cross-head movable with said feed-bar and disposed in the path of the collar on the spacing-bar, and a series of keys each having operative connection with one or more of the punch-slides, substantially as described.

13. In a perforating-machine of the class described, the combination of a cross-head carrying fixed thereto a group of feed-hole punches,

a plurality of character-punches having means for operating the same singly or in groups, a ribbon-feed mechanism including a feed-wheel and a pawl-rod, a spacing-key 5 slide connected to the cross-head for operating the feed-hole punches independently of the character-punches, and connections between the spacing-key slide and the pawl-rod to actuate the feed mechanism automatically 10 for the advancement of the ribbon subsequent to the withdrawal of the punches.

14. In a perforating-machine of the class described, the combination of a cross-head equipped with feed-hole punches, a plurality 15 of character-punches having means for actuating the same singly or in groups, a ribbon-feed mechanism including a revoluble element and a slideable rod, a spacing-key slide connected to the punch-carrying cross- 20 head and provided with a collar, and a secondary cross-head attached to the slideable rod and disposed in the path of said collar, whereby the ribbon-feed mechanism will be moved to an abnormal position on the active 25 movement of the punches.

15. In a perforating-machine of the class described, the combination of a cross-head equipped with feed-hole punches fixed thereto, a plurality of character-punches having 30 means for actuating the same singly or in groups, a ribbon-feed mechanism, a spacing-key slide connected to the punch-carrying cross-head, and a secondary cross-head connected to an element of the ribbon-feed mechanism and having operative relation to the spacing-key slide and the character-punch-actuating mechanism for controlling the ribbon-feed mechanism from either of said punch mechanisms.

40 16. In a perforating-machine of the class described, the combination of shouldered slides having character-punches, a cross-head equipped with feed-hole punches, a secondary cross-head disposed in the path of the 45 character-punch slides, a ribbon-feed mechanism operatively connected with the secondary cross-head, and a spacing-key slide connected to the punch-carrying cross-head and having means for actuating the ribbon-feed 50 mechanism through the secondary cross-head.

17. In a perforating-machine of the class described, the combination of shouldered slides having character-punches, a cross-head disposed in the path of the shoulders on said 55 slides, feed-hole punches on the cross-head, a spacing-key slide connected with the cross-head and adapted to actuate the feed-hole punches independently of the character-punches, means for actuating the character- 60 punches singly or in groups and causing the shouldered slides thereof to move the cross-head and the feed-hole punches to active positions simultaneously therewith, and a ribbon-feed mechanism having actuating devices 65 which are controllable by the feed-hole punch mechanism and by the character-punch mech-

anism to be actuated either collectively or individually.

18. In a perforating-machine of the class described, a ribbon-feed mechanism comprising 70 a shaft having a ratchet and a feed-wheel, a slideable rod provided with a collar, a check-finger clamped to said rod, a sleeve fitted idly to the rod between the collar and the check-finger, and a feed-pawl mounted on the sleeve, 75 substantially as described.

19. In a perforating-machine of the class described, the combination of a plurality of shouldered slides having character-punches, means for actuating said slides singly or in 80 groups, a cross-head disposed in the path of the character-punch slides and equipped with a group of feed-hole punches, a spacing-key slide connected adjustably to said cross-head, and a ribbon-feed mechanism, substantially 85 as described.

20. In a perforating-machine of the class described, the combination of a plurality of double-shouldered slides carrying character-punches, a normally-retracted cross-head 90 engaging with one set of shoulders on the slides and equipped with feed-hole punches, another cross-head idly disposed in the path of the other set of shoulders on the character-punch slides, a ribbon-feed mechanism including a 95 rod connected to the last-mentioned cross-head, and a spacing-key slide attached to the first cross-head and having means for actuating the second cross-head.

21. A perforating-machine for telegraphic 100 paper comprising a keyboard having keys mounted thereon, key-rods actuated by said keys, a punch-head, a series of slides mounted transversely of said key-rods and carrying punches slidably mounted in apertures in the 105 punch-head, and selective means carried by each key-rod to reciprocate said slides longitudinally.

22. A perforating-machine for telegraphic 110 paper comprising a keyboard having keys mounted thereon, parallel key-rods actuated by said keys, a series of slides mounted transversely of said rods, selective connections between each key-rod and the appropriate slides, whereby to advance the proper slides to form 115 the punch-holes corresponding to a telegraphic code, a punch-head, punches carried by the ends of said slides and mounted to reciprocate in said punch-head, and means for feeding a strip of telegraphic paper across the 120 end of the punch-head.

23. A perforating-machine for telegraphic 125 paper comprising a keyboard having depressible keys mounted thereon, parallel shafts connected with the respective keys and mounted transversely of the frame, a series of parallel punch-slides mounted to reciprocate longitudinally and transversely over said key-shafts, projecting studs carried by each slide, and means upon the respective key-shafts for 130 engaging said studs, whereby the depression of the key causes the appropriate punch-

slides to be advanced to punch the telegraphic paper.

24. A perforating-machine for telegraphic paper comprising a rectangular frame having a keyboard at the front portion thereof, depressible keys mounted in said keyboard, individual key-shafts mounted in parallel relation extending from front to rear of said frame and adapted to be given an oscillating motion by the depression of said keys, a series of appropriately-arranged punch-slides mounted in parallel relation transversely over said key-shafts, projecting studs carried by each of said slides, rock-arms carried by each key-shaft adapted to engage the corresponding studs on the slides, a punch-head having parallel apertures, punches slidable in said apertures and mounted upon the ends of the punch-slides, and means for feeding a telegraphic tape across said punch-head.

25. A perforating-machine for telegraphic paper comprising a frame having a keyboard mounted in the front portion thereof, a series of depressible keys mounted in said keyboard, rock-shafts connected individually with the respective keys to be rocked thereby on the depression of the keys and extending in parallel relation transversely of said frame, a series of punch-slides slidably mounted in parallel relation longitudinally of the machine and transversely of said rock-shafts and arranged in two groups one below the other, studs mounted on each slide, rock-arms mounted on the respective rock-shafts coöperating with the studs so as by the depression of a key to advance the corresponding slides necessary to form the punch-holes of a telegraphic code, a punch carried upon the ends of each of said slides, a punch-head having two parallel rows of apertures in which the respective groups of punches slide, and means for intermittently feeding a telegraphic tape across said punch-head.

26. A perforating-machine for telegraphic paper comprising a frame having a keyboard in the front thereof, a series of key-shafts mounted to extend transversely of the machine and connected with the respective keys to be operated thereby, a series of longitudinal horizontal punch-slides mounted to slide longitudinally transversely over said key-shafts, means connecting the respective key-shafts with the appropriate punch-slides to advance the latter upon the depression of a key, a punch-head having parallel rows of apertures therein, and a series of punches carried upon the ends of the slides and operating in said apertures, the ends of said punches being arranged in staggered relation, whereby the simultaneous advancement of the punch-slides caused by the depression of a key will punch the holes through the paper successively.

27. In a perforating-machine for telegraphic paper, an intermittent-feed mechanism for the tape comprising a vertical feed-shaft, a feed-wheel having pegs around its

periphery adapted to engage the central row of holes in the tape, a ratchet-wheel mounted upon the feed-shaft, a feed-rod mounted adjacent to the ratchet-wheel and adapted to reciprocate longitudinally, a pawl mounted upon and operated by said feed-rod and engaging with the teeth of said ratchet-wheel, a check-pawl formed by a hooked finger carried upon said feed-rod and adapted to normally engage the teeth of said ratchet-wheel at the end of a feeding movement of the rod, whereby to prevent an excessive advancement of the wheel, and a stationary detent engaging with the teeth of the ratchet-wheel to prevent its back motion.

28. In a perforating-machine for telegraphic paper, the combination of a feed-shaft, a feed-wheel mounted thereon adapted to grasp and advance the paper, a ratchet-wheel mounted upon the feed-shaft, a feed-rod mounted to reciprocate longitudinally adjacent to said ratchet-wheel, a pawl mounted upon said feed-rod to engage the teeth of said ratchet-wheel, and a check-finger adapted to engage the rear face of the ratchet-teeth at the end of each forward movement of the wheel to prevent improper advancement of the latter.

29. In a perforating-machine for telegraphic paper, a feed mechanism comprising a feed-shaft, a feed-wheel mounted thereon adapted to grasp and advance the paper, a ratchet-wheel mounted on said shaft, a feed-rod mounted to reciprocate longitudinally adjacent to said ratchet-wheel, a collar loosely mounted on said feed-rod, a pawl carried by said collar and engaging the teeth of said wheel, a check-pawl formed by a hooked finger adjustably mounted on the end of said rod and adapted to engage the rear face of the ratchet-teeth at the end of each forward movement of the wheel, a spring operating to retract said feed-rod, and means for advancing the feed-rod against the spring.

30. A perforating-machine for telegraphic paper comprising a frame having a keyboard on the front thereof, a series of depressible keys mounted in said keyboard, a series of parallel key-rods mounted transversely of the frame and adapted to be operated by the respective keys, a series of parallel punch-slides mounted transversely of said key-rods and adapted to reciprocate longitudinally in the frame, selective means connecting each key-rod with the appropriate slides to advance the latter, a punch-head, a series of punches carried by the reciprocative slides and operating in apertures in said head, a cross-head mounted to reciprocate in a longitudinal slot formed between the adjacent edges of the punch-slides, springs acting upon said cross-head to retract the latter, and a series of feed-hole punches carried by said cross-head and fixed thereto, whereby the advancement of any one or more of said punch-slides will cause the advancement of the cross-head and the springs upon the cross-head will cause the

retraction of the advanced slides to their normal position.

31. A perforating-machine for telegraphic paper comprising a frame having a keyboard on the front thereof, a series of depressible keys mounted in said keyboard, a series of parallel key-rods mounted transversely of the frame and adapted to be operated by the respective keys, a series of parallel punch-slides mounted transversely of said key-rods and adapted to reciprocate longitudinally in the frame, selective means connecting each key-rod with the appropriate slides to advance the latter, a punch-head, a series of punches carried by the reciprocative slides and operating in apertures in said head, a cross-head mounted to reciprocate in a longitudinal slot formed between the adjacent edges of the punch-slides, springs acting upon said cross-head to retract the latter, and a series of feed-hole punches carried by said cross-head and fixed thereto, whereby the advancement of any one or more of said punch-slides will cause the advancement of the cross-head and the springs upon the cross-head will cause the retraction of the advanced slides to their normal position, in combination with an independent spacing-rod secured to said cross-head, an independent spacing-key, a key-rod actuated by said key, and a connection between said key-rod and spacing-rod, whereby to advance said spacing-rod and cross-head and the feed-hole punches carried thereby independently of the punch-slides.

32. A perforating-machine for telegraphic paper comprising a frame having a keyboard on the front thereof, a series of depressible keys mounted in said keyboard, a series of parallel key-rods mounted transversely of the frame and adapted to be operated by the respective keys, a series of parallel punch-slides mounted transversely of said key-rods and adapted to reciprocate longitudinally in the frame, selective means connecting each key-rod with the appropriate slides to advance the latter, a punch-head, a series of punches carried by the reciprocative slides and operating in apertures in said head, a cross-head mounted to reciprocate in a longitudinal slot formed between the adjacent edges of the punch-slides, springs acting upon said cross-head to retract the latter, and a series of feed-hole punches carried by said cross-head and fixed thereto, whereby the advancement of any one or more of said punch-slides will cause the advancement of the cross-head and the springs upon the cross-head will cause the retraction of the advanced slides to their normal position, in combination with an independent spacing-rod secured to said cross-head, an independent spacing-key, a key-rod actuated by said key, a connection between said key-rod and spacing-rod, whereby to advance said spacing-rod and cross-head and the feed-hole punches carried thereby independently of the punch-slides, and step-by-

step feed mechanism operated by the advancement of said cross-head.

33. A perforating-machine for telegraphic paper comprising a frame having a keyboard on the front thereof, a series of depressible keys mounted in said keyboard, a series of parallel key-rods mounted transversely of the frame and adapted to be operated by the respective keys, a series of parallel punch-slides mounted transversely of said key-rods and adapted to reciprocate longitudinally in the frame, selective means connecting each key-rod with the appropriate slides to advance the latter, a punch-head, a series of punches carried by the reciprocative slides and operating in apertures in said head, a cross-head mounted to reciprocate in a longitudinal slot formed between the adjacent edges of the punch-slides, springs acting upon said cross-head to retract the latter, and a series of feed-hole punches carried by said cross-head and fixed thereto, whereby the advancement of any one or more of said punch-slides will cause the advancement of the cross-head and the springs upon the cross-head will cause the retraction of the advanced slides to their normal position, in combination with an independent spacing-rod secured to said cross-head, an independent spacing-key, a key-rod actuated by said key, and a connection between said key-rod and spacing-rod, whereby to advance said spacing-rod and cross-head and the feed-hole punches carried thereby independently of the punch-slides, and step-by-step feed mechanism comprising a vertical feed-shaft, a feed-wheel carried thereby and having means to grasp and advance the tape, a ratchet-wheel mounted on said feed-shaft, a reciprocative rod having a pawl engaging the teeth of said ratchet-wheel, a cross-head carried by the rear end of said rod, a spring acting to retract the latter, and a stop carried by said spacing-rod whereby the advancement of the first-named cross-head is adapted to cause the advancement of said feed-rod to turn said ratchet-wheel.

34. A perforating-machine for telegraphic paper comprising a frame having a keyboard in the front thereof, a series of depressible keys mounted in said keyboard, a series of rock-shafts mounted in parallel relation transversely of said frame and having arms adapted to be actuated by the respective keys, appropriately-positioned rock-arms carried by each rock-shaft, a series of shouldered punch-slides mounted in parallel relation to slide longitudinally from side to side of said frame and extending transversely across said rock-shafts and arranged in two groups one under the other, said punch-slides having their rear ends spread out and separated from one another and their front ends arranged close together, projecting studs carried by each of said punch-slides and suitably positioned to be actuated by said rock-arms, a cross-head mounted to reciprocate in a slot

formed by opposite rectangular notches in the adjacent edges of the forward portions of said punch-slides, a punch-head and die-block between which the tape is adapted to 5 be drawn, a character-punch mounted upon the end of each punch-slide and adapted to reciprocate in an aperture in the punch-head, a series of feed-hole punches fixedly mounted upon said cross-head and operating in a central row of apertures in said punch-head, a spacing-rod fixed to a depending tongue upon said cross-head and adapted to reciprocate therewith, springs acting upon the cross-head to retract 10 the same, a projecting stud carried by said spacing-rod, an independent rock-shaft carrying an arm engaging the said stud, a spacing-key adapted to oscillate said arm, whereby said feed-hole punches may be independently advanced and the advancement 15 of any one or more of said character-punches causes the simultaneous advancement of said feed-hole punches.

35. A perforating-machine for telegraphic paper comprising a frame having a keyboard 25 in the front thereof, a series of depressible keys mounted in said keyboard, a series of rock-shafts mounted in parallel relation transversely of said frame and having arms adapted to be actuated by the respective keys, 30 appropriately-positioned rock-arms carried by each rock-shaft, a series of shouldered punch-slides mounted in parallel relation to slide longitudinally from side to side of said frame and extending transversely across said 35 rock-shafts and arranged in two groups one under the other, said punch-slides having their rear ends spread out and separated from one another and their front ends arranged close together, projecting studs carried by 40 each of said punch-slides and suitably positioned to be actuated by said rock-arms, a cross-head mounted to reciprocate in a slot formed by opposite rectangular notches in the adjacent edges of the forward portions of said 45 punch-slides, a punch-head and die-block between which the tape is adapted to be drawn,

a character-punch mounted upon the end of each punch-slide and adapted to reciprocate in an aperture in the punch-head, a series of feed-hole punches fixedly mounted upon said cross-head and operating in a central row of apertures in said punch-head, a spacing-rod fixed to a depending tongue upon said cross-head and adapted to reciprocate therewith, springs acting upon the cross-head to retract 50 the same, a projecting stud carried by said spacing-rod, an independent rock-shaft carrying an arm engaging the said stud, a spacing-key adapted to oscillate said arm, whereby said feed-hole punches may be independently advanced and the advancement of any one or more of said character-punches causes the simultaneous advancement of said feed-hole punches, a feed mechanism comprising a vertical feed-shaft, a toothed feed-wheel 55 carried thereby, a ratchet-wheel also mounted upon said feed-shaft, a reciprocating feed-rod mounted adjacent to said ratchet-wheel, a loose collar carrying a pawl mounted on said rod and engaging the teeth of said ratchet-wheel, a check-pawl likewise mounted upon said feed-rod and adapted to engage the rear face of the ratchet-teeth, a spring attached to one end of said feed-rod and adapted to retract the latter, a second cross-head adjustably mounted upon said feed-rod and operating in a slot formed by opposite rectangular notches formed in the adjacent edges of said punch-slides, and an adjustable stop-collar carried by the spacing-rod and adapted to 70 abut against said second cross-head, whereby the advancement of the spacing-rod or cross-head attached thereto causes the simultaneous advancement of the feed mechanism, substantially as described.

In witness whereof I have hereunto set my hand in the presence of two witnesses.

GEORGE HASTINGS HACKETT.

Witnesses:

D. L. MCPHEE,
F. T. LE MORNE.
